D. Ullam.

Rotary Steam Engine.

Patented Mar. 23, 1836.

David Ullam of Greenburg, Pennsylvania
Letters Patent

The Schedule referred to in these Letters Patent and making part of the same containing a description in the words of the said David Ullam himself of his Improvement in the Rotary Steam Engine.

Be it known that I David Ullam of Greenburg, in the County of Westmoreland, and State of Pennsylvania, have invented a new and useful improvement in the Rotary Steam Engine, which is described as follows, reference being had to the annexed drawings of the same, making part of this specification.

This Engine consists of two circular plates, embracing a circular rim, secured together by bolts, forming a circular chamber, within which revolves a wheel driven by the expansive force of steam admitted through a tube in the rim and acting on a stop projecting from the periphery of the wheel and filling the steam chamber; it receives this steam through a valve, ^{the valve, a sliding valve, working in an opening in the rim,} which valve is operated by the machinery of the Engine. The shaft of the revolving wheel which conveys the power to machinery passes thro' round the aperture in the centre of the circular plates. The circular plates marked a. in the annexed drawings, are made of any convenient diameter and thickness, and have two concentric circular grooves, b. c. cut in them, on the sides towards the inside of the steam chamber, one of which is to receive the rim and the other the packing. There are also apertures for the screw bolts, d. which secure the plates together; & an aperture in the centre for the shaft, e. of the revolving wheel. In the groove for the packing, and below it is, placed a flat ring, f. which is intended to force the packing close against the revolving wheel by screws, g. which pass through the plates and act upon set-screws, forcing it with the packing against the wheel. The rim, h. is of the same diameter as the outer concentric groove in which it is to be placed, and of any suitable depth and as thick as the groove is wide. It has three openings in its circumference, one is for the introduction of

the steam; another, $R.$ for its discharge, and a third, $C.$ for the valve. The revolving circular wheel, $m.$ which revolves within the ring, being of a less diameter than the iron, leaves a space $n.$ below the periphery of the wheel, and the inside of the iron, for the steam, which acts on a projection or slope $o.$ of the wheel. This slope fills the space just mentioned, for the steam. The wheel is fastened immovably to its shaft, which passes thro' a aperture in the center of the circular plates, and is, for conveying the power to my machinery, as required. The two plates are put together so as to embrace the iron, and form a circular chamber for the steam, and for the circular air, leaving therein, and are secured together by the screw bolts before mentioned. The packing is placed against the sides of the revolving wheel by the screws and rings, for preventing the escape of the steam.

The slope is made to work light by placing packing over it, and securing the same by a screw and plate. There may be one or more slope of the steam along the steam chamber thro' the introduction tube & passing between the valve and the slope of the wheel and by its expansive force turns the wheel, and when the steam arrives at the introduction tube it escapes into the atmosphere. The valve is withdrawn by the wedge-like form of the slope and returned at the moment required by a spring or weight or by an attachment of machinery for that purpose. The motion of the engine may be made moving slow by the addition of a balance wheel.

What I claim as my invention, and which I desire to secure by Letters Patent, consists in the before described ^{Steam} Rotary Engine.
